UNITED STATES PATENT OFFICE.

CHARLES H. WARREN, OF ATLANTA, GEORGIA, ASSIGNOR TO DRAPER CORPORATION, OF HOPEDALE, MASSACHUSETTS, A CORPORATION OF MAINE.

LOOM FEELER MECHANISM.

1,332,699.

Specification of Letters Patent.

Patented Mar. 2, 1920.

Application filed January 9, 1919. Ser. 11 270,269.

To all whom it may concern:

Be it known that I, CHARLES H. WARREN, of Atlanta, in the county of Fulton and State of Georgia, have invented an Improved Loom Feeler Mechanism, of which the following is a specification.

The present invention consists of certain improvements upon the impact type of side slipping loom feeler mechanism such as is set forth in Letters Patent of the United States of Edward S. Stimpson, No. 1,309,226, July 8, 1919, and in an application of said Stimpson, Serial Number 245,565, filed July 18, 1918.

15. In accordance with said patent and application, the impact of the forwardly moving bobbin, or other weft carrier, tends to displace the feeler laterally and lengthwise of the weft carrier but this movement is restrained by the contact between the weft 20 and the feeler tip. When, however, the bobbin, or other weft carrier, is bared where it contacts with the feeler tip, the feeler tip slides along the smooth surface of the weft 25 carrier and this movement is utilized in setting into action a train of mechanism which replenishes the weft. It occasionally happens in looms equipped with such feeler mechanism that the shuttle is misplaced 30 when in the shuttle box at the detecting side of the loom so that the weft does not contact with the feeler tip but said tip is encountered by a smooth portion of the bobbin or shuttle such as the front weft carrier 35 holding spring such as is employed in the well known Northrop loom. The effect of such encounter is the same as that of the smooth bared weft carrier, namely to cause the feeler to slip sidewise and hence to bring 40 about premature weft replenishment. This may occur when the weft carrier has a full load of weft or a supply of weft ample for further weaving so that labor is lost in replacing such prematurely discharged weft 45 carriers in the weft replenishing magazine. The first object of the present invention is to prevent such premature calls for weft replenishment and one of the present improvements consists in the construction and 50 organization which achieve this object.

A second improvement resides in the particular construction of the teeth of the feeler tip which is especially effective when weaving with coarse wefts.

The improvements are illustrated in the 55 accompanying drawings in which—

Figure 1, is a plan view of so much of the detecting side of the loom as is necessary for an understanding of the improvement. In this figure the front walls of the shuttle and 60 of the shuttle box are shown in section, and the parts are shown in the position which they occupy just as the weft first encounters the feeler tip during the forward swing of the lay on its detecting beat. Figs. 2, and 65 3, are views of the feeler tip and of a portion of the weft and of the bobbin on an enlarged scale illustrating their relation at different stages of the operation of the loom. Fig. 2, shows the initial contact between the weft 70 and feeler tip. Fig. 3, illustrates approximately the condition which occurs following the encounter of weft and feeler tip, indicating a penetration of the teeth into the weft. Fig. 4, is a view similar to Fig. 1, 75 showing an encounter between the front bobbin holding spring and the feeler tip. Fig. 5, is a view illustrating the lateral slip of the feeler along a bared bobbin, a part of the feeler mechanism being shown in horizontal section. Fig. 6, is a detailed vertical section in the plane indicated in the line 6—6 in Fig. 2. Figs. 1, and 5, show the shuttle in normal position, and Fig. 4, shows 80 it misplaced.

The improvements constituting the present invention reside in the construction of the feeler tip A, and its teeth and in the relation between such feeler tip and the lay and shuttle, the shuttle being provided with 90 a specially elongated front opening to cooperate with the new feeler tip. Otherwise, the drawings illustrate the feeler mechanism of the aforesaid patent and application.

The feeler comprises the feeler tip A, and 95 a feeler arm B. The feeler arm is mounted so as to both slide and swing and it is shown as inclined to the fore and aft swing of the lay and with the feeler tip offset laterally as compared with the forward end of the 100 feeler arm. As a consequence of this disposition of the feeler arm the impact of the forwardly moving bobbin C, tends to swing the feeler arm laterally and lengthwise of the bobbin. So long, however, as weft D, 105 is present on the bobbin opposite the feeler tip the engagement of the weft with the feeler tip teeth E, prevents such lengthwise

slipping. Fig. 3, illustrates to an exaggerated degree, for the sake of clearness, penetration of the teeth E, into the weft D, to prevent the slipping of the tip lengthwise of the bobbin C.

When, however, the feeler tip teeth encounter the smooth surface of the bared bobbin, the impact of the bobbin on the inclined feeler causes the feeler to swing and the teeth E, to slip along the bobbin to the position shown in Fig. 5. This lateral swing is utilized to set the weft replenishing train into action. The feeler tip A, is secured in the forked rear end of the feeler arm by a screw F.

The accompanying drawings illustrate only enough of the feeler supporting and co-operating mechanism to enable the sliding and swinging movements of the feeler arm to be understood, since in these respects the mechanism is identical with that shown in the aforesaid patent. The feeler arm B, is mounted on a bracket I, attached to a lateral extension J, of the breast beam. A front guide K, is swiveled to the forward end of the bracket, turning on a vertical axis. This front guide has a through-aperture through which the front end of the feeler arm extends and slides. At its rear end the feeler arm extends through a broad guideway in the bracket, the side margins of this passageway being indicated at L, L. The top of this guideway is closed by a cap M, which with the bottom of the bracket confines the feeler arm against vertical movement. Secured to the feeler arm near its middle is a slide N, which slides on horizontal ways O, of the bracket. A spring Q, surrounds the feeler arm between the slide N, and the swiveled guide K, and normally holds the feeler arm in its rearward position with the slide against the shoulders of the bracket which support the cap M, as shown in Fig. 1. The feeler arm is also maintained by the spring against the outer wall L, of the rear guideway. The swiveled guide is offset laterally and outwardly with respect to the rear guideway so that the feeler arm stands at an angle to the fore and aft swing of the lay and the bobbin (or the weft thereon) encounters the tip A, along a fore and aft path nearer the tip of the bobbin than a parallel path intersecting the swiveled guide. So long as the weft on the bobbin encounters the teeth of the tip the resistance thus offered prevents any slipping of the tip lengthwise of the bobbin. Accordingly as the lay moves forward after the first encounter of the weft with the tip there is no sliding of the tip along the weft; but, during the completion of the forward movement of the bobbin, the feeler arm is moved forwardly compressing the spring Q. During this normal action there is a slight inward swing (to the right) of the feeler

arm permitted by the turning of the swiveled guide. When the bobbin is bare opposite the feeler tip there is a further inward lateral swing of the feeler arm to the right, as shown in Fig. 5, and this additional swing is utilized to set in action the train of weft replenishing mechanism.

This functional swing of the feeler arm under the impact of the bare bobbin causes the feeler arm to encounter a controller X, and move it laterally inward. This controller is mounted in a transverse guide-way Y, of the bracket J, and it has a slot Z, through which the feeler arm passes. This slot is sufficiently wider than the feeler arm so that the normal swing of the feeler arm has no effect on the controller. When, however, the functional swing of the feeler arm is imparted to it by the lengthwise movement of the feeler tip along the bobbin the controller is slid laterally inward. This lateral movement of the controller is utilized to bring about weft replenishment as explained in detail in the aforesaid patent. After the functional action has occurred a fixed cam W, on the bracket acts upon a downwardly extending projection V, (indicated in dotted lines only, Fig. 4) on the feeler arm to restore the feeler arm to its normal position as it retreats under the influence of the spring Q, as set forth in said patent.

The weft D, is so wound on the bobbin (or other weft-carrier) that there is a sufficient amount (as indicated in Fig. 5) to continue the weaving after the feeler tip has performed its functional slip and until weft replenishment has been effected.

As shown in Figs. 1, and 4, the head of the bobbin C, is held by spring jaws 10, carried by the shuttle 11, as is customary in the well known Northrop loom, as illustrated, for example, in United States Letters Patent of Edward S. Stimpson, No. 1,074,908, October 7, 1913. The front wall of the shuttle is provided with an opening or window 12, for the reception of the feeler tip. The front wall of the shuttle box at the detecting end of the lay 13, has two sections 14, and 15, separated from each other so as to leave an opening for the reception of the feeler tip. Each of these wall sections is provided with a covering 16, of leather or equivalent material. In all of these respects the organization is similar to that previously used in the Northrop loom excepting that the shuttle slot or window 12, is elongated inwardly toward the bobbin tip to a greater distance than usual to accommodate the special construction of the feeler tip.

The feeler tip A, is formed with an elongated toe 17, projecting laterally beyond the rear end of the feeler arm B, and terminating in an inclined stop end 18. When the feeler tip slips sidewise along the bared bob-

bin, as shown in Fig. 5, thereby moving the controller X, laterally inward to initiate the action of the weft replenishing mechanism, the elongated toe 17, of the feeler tip slips 5 to a position behind the outer end of the shuttle box front section 15, as shown in Fig. 5. This movement is permitted by the elongated inner end 19, of the shuttle slot 12. The fore and aft width of the toe 17, 10 is less than the distance between the shank of the bobbin and the front wall of the shuttle box so that ample space is afforded for the entrance of the toe as shown in Fig. 5, but such width is greater than the thickness 15 of the front wall of the shuttle.

In the event, however, that the shuttle is misplaced in the shuttle box at the detecting side of the lay so that the feeler tip encounters the front bobbin spring 10, instead 20 of the weft, as indicated in Fig. 4, the stop end 18, of the feeler tip abuts against the outer end of the wall section 15, before the feeler has slipped sidewise far enough to have any effect upon the controller, as illustrated in Fig. 4. The slot Z, in the controller X, is wide enough to permit some lateral movement of the feeler tip without any movement being imparted to the controller. The organization is such that the 25 feeler tip encounters the shuttle box wall section 15, and is stopped thereby before the feeler arm moves sidewise far enough to transmit lateral movement to the controller. As compared with the construction shown in 30 the aforesaid application of Stimpson, the slot Z, in the controller is somewhat elongated and sufficiently so to permit the feeler tip to be stopped by the shuttle box wall section 15, just as the feeler arm has traversed the slot Z, but has not yet moved far enough to slide the controller. Accordingly, 35 the weft replenishing train of mechanism is not set into action, and there is no ejection of the full or partially full bobbin as would 40 be the case if the feeler tip were permitted to slip sidewise to its full extent when encountered by the front bobbin spring 10, of the shuttle. In setting the feeler mechanism on the loom, the distance between the 45 stop end 18, and the co-operating covered wall section 15, 16, should be no greater than the length of the part of the slot Z, which is unoccupied by the arm B, as shown in Fig. 1.

50 The shuttle tip A, is rigidly and immovably held within the rear end of feeler arm B, and the ends of the teeth E, are arranged in an arc of a horizontally extending circle convex toward the bobbin as in the aforesaid 55 Stimpson application 245,565 excepting that the arc is of smaller radius. In said application the rear end of each tooth is rounded along a horizontal plane but is straight vertically. In accordance with the present in- 60 vention the end of each tooth as shown in

Figs. 2 and 3 is blunt horizontally. That is to say, looking down upon the teeth as in these figures, the end of each tooth extends horizontally in a straight line. Any horizontal section of a tooth shows its end as 70 a straight line. Hence each tooth is straight and blunt horizontally; that tooth which penetrates the weft most deeply being parallel horizontally with the longitudinally extending portion of the bobbin as shown 75 in Fig. 3. But, vertically, each tooth is pointed, as shown in Fig. 6, this pointing being obtained by rounding the end of the tooth in a vertical direction. Hence, as shown in Fig. 6, any vertical section of the 80 tooth, shows its end as a round point. Therefore, as shown in Fig. 6, a vertical section through the bobbin and the feeler tip exhibits the contiguous surfaces as convex toward each other. In other words, the 85 end of each tooth is cylindrical with the axis of the cylinder extending horizontally. Owing to this construction each tooth is blunt and straight horizontally, and is pointed vertically. The end of each tooth 90 meets each of its side walls by a sharp corner 95 20. This shape of tooth is particularly efficacious when coarse wefts are used. The rounding of the teeth vertically permits sufficient penetration into the weft and the sharp inner corners prevent premature slippage. The arrangement of the teeth in a horizontally extending circular arc of small radius convex to the bobbin brings the sharp inner corners 20, into effective action. 100

I claim:

1. A loom feeler mechanism having a side slipping feeler with a toothed tip having a laterally projecting toe with its fore and aft width less than the distance between the 105 bared surface of the weft carrier and the front wall of the shuttle box at the detecting side of the loom and greater than the thickness of the front wall of the shuttle, said tip terminating in a stop end, in combination with the lay having an opening in the shuttle box at the detecting end of the lay for the reception of the feeler tip, and a shuttle having an elongated opening in its front wall for the reception of the 110 feeler tip, 115 said elongated opening extending inwardly beyond the opening in the shuttle box in the direction in which the feeler tip slips.

2. A loom feeler mechanism having a side slipping feeler with a tip having a laterally projecting toe with its fore and aft width less than the distance between the 120 bared surface of the weft carrier and the front wall of the shuttle box at the detecting side of the loom, said tip terminating in a stop end, in combination with the lay having at its detecting end an opening in the 125 shuttle box for the reception of the feeler tip, and a shuttle having an elongated opening in its front wall for the reception of the 130

feeler tip, said elongated opening extending beyond the opening in the shuttle box in the direction in which the feeler tip slips.

3. A loom feeler mechanism having a side slipping feeler with a plurality of teeth arranged in a horizontally extending arc of a circle convex toward the bobbin, each tooth at its rear feeling end being straight and blunt in horizontal planes and curved in vertical planes with sharp corners between each side of the tooth and its rear feeling end.

4. A loom feeler mechanism having a side slipping feeler with a plurality of teeth arranged in a horizontally extending arc of a

circle convex toward the bobbin, each tooth at its rear feeling end being blunt in horizontal planes and pointed in vertical planes with a sharp corner between the inner side of the tooth and its rear feeling end.

20

5. A loom feeler mechanism having a side slipping feeler with a plurality of teeth arranged at varying distances from the bobbin, each tooth at its rear feeling end being blunt in horizontal planes and pointed in vertical planes.

25

In witness whereof, I have hereunto signed my name.

CHARLES H. WARREN
